UNITED STATES PATENT OFFICE.

WINFIELD P. PEMBROKE, OF ROCHESTER, NEW YORK.

CARBURETER.

1,236,004.

Specification of Letters Patent.

Patented Aug. 7, 1917.

Application filed March 16, 1914. Serial No. 824,886.

To all whom it may concern:

Be it known that I, WINFIELD P. PEMBROKE, of Rochester, in the county of Monroe and State of New York, have invented 5 certain new and useful Improvements in Carbureters; and I do hereby declare the following to be a full, clear, and exact description of the same, reference being had to the accompanying drawings, forming a part 10 of this specification, and to the reference-numerals marked thereon.

My present invention relates to carbureters adapted to be used in conjunction with explosive engines, and it has for its 15 object to provide an apparatus for the vaporizing of liquid hydrocarbon fuels, the parts of which are arranged to supply the requisite proportions of air and fuel in the required volume under varying conditions and 20 especially to automatically control or regulate the relative proportions of the fuel and air required by an engine when operating under high duty conditions.

My invention has for its further object 25 to provide a carbureter having two or more sets of air and fuel inlets, one set being adapted to supply the carbureted mixture under low speed conditions, while the other set of inlets is arranged to be brought into 30 action when the engine develops speed or power above a predetermined point. My invention also comprehends the controlling of auxiliary air and fuel inlets by means of normally closed valves which are independently opened by the pressure of the inrush- 35 ing air together with mechanism operated by the air valve for forming a stop limiting the relative opening movement of the fuel valve, which is further capable of man- 40 ual adjustment. To these and other ends the invention consists in certain improve- 45 ments and combinations of parts, all as will be hereinafter more fully described, the novel features being pointed out in the claims at the end of the specification.

In the drawings:

Figure 1 is a side elevation of a carbureter constructed in accordance with my invention;

50 Fig. 2 is a top plan view thereof, and

Fig. 3 is an enlarged cross sectional view, taken on the line 3'-3' of Fig. 2.

Similar reference numerals throughout the several figures indicate the same parts.

55 A carbureter embodying my present invention is capable of automatically control-

ling the quantity of fuel oil or gasoline and the required volume of air necessary to be supplied to form the charge admitted to an engine or motor under all the varying conditions encountered in its operation from the lowest speed at which it is capable of working to the highest speed or point where the engine is delivering its maximum horsepower, certain features of adjustment being 60 provided to enable the operator to regulate the mechanism to produce its full efficiency under varying atmospheric changes and to compensate for differences in the gravity or volatility of the liquid hydrocarbon fuel 65 employed at different times. In the illustrations showing one embodiment of my present invention the carbureter is illustrated as comprising a shell or body 1 having a horizontal passage A opening into the 70 vertical passage B at one end forming the outlet which, it will be understood, is adapted to be connected to the intake manifold of the motor or engine to which the carbureter is applied. At its other end the passage 75 A terminates in the chamber C which is closed at its ends by air valves, as will be presently described, which, when opened, form inlet passages for supplying the air required in forming the carbureted mixture 80 used by the engine when operating under high duty. Opening into the bottom of the casing 1 are a plurality of fuel discharge nozzles, in the present instance two of these being shown, and indicated by D and E, the former being adapted to supply the liquid fuel under ordinary low speed requirements of the engine, while the latter forms the auxiliary fuel inlet which is brought into 85 action when the speed of the engine or the working load is increased beyond a predetermined point. The auxiliary nozzle E is associated with the air inlets of the chamber C and like these inlets it is also normally closed by a valve head which is automatically opened by the atmospheric pressure created by the partial vacuum produced 90 in the carbureter casing.

The fuel inlet D is arranged preferably in central alinement with the outlet passage B 105 and below the bottom of the passage A, its discharge end being surrounded by a choke collar or Venturi tube d which forms a continuation of the main air inlet F. The size, shape and general position of the tube d 110 and nozzle D is such that the force of the suction created by the inrushing air in the

zone of the nozzle will lift or draw therefrom gasoline, or other hydrocarbon liquid, in such proportions as may be desired for operating the engine within a given range 5 of low power speeds. For instance, when the power developed is expressed in miles per hour, as is the case where the motor is mounted upon an automobile, the range of speed cared for by the main air intake F 10 and its associated nozzle D will be from the lowest cranking speed to about seventeen miles per hour. The additional fuel and air supplying the larger volume of carbureted mixture required for higher speeds are furnished by the auxiliary ports or inlets operating in conjunction with the main air and fuel inlet.

The auxiliary fuel inlet nozzle E opens into the bottom of the air passage or chamber A in the casing 1, the liquid being supplied thereto through the central perforation e, corresponding to the perforation d' of the nozzle D and with which it communicates by means of the passage e'. The liquid 25 is fed into said passages from the passage e² leading from the usual float chamber, indicated by e³ and illustrated in Fig. 2. The upper end of the nozzle E is enlarged to provide the head E' through which 30 extends a series of circumferentially arranged perforations E² which open into the chamber A and form the valve operating air passages. The upper end of the head E is preferably flattened forming a valve seat 35 with which co-operates the valve head G having the central tapered plug g fitting the upper end of the passage e and forming a graduated valve controlling the fluid inlet as set forth in my copending application 40 Serial No. 824,885, filed March 16, 1914, which has matured into Patent No. 1,192,106 July 25, 1916. The head G extends over the inner ends of the perforations E² and normally closes them so that when a partial 45 vacuum is created in the passage A the air endeavoring to enter through said perforations will tend to unseat the valve head, at the same time withdrawing the plug g from the fuel passage e and as the passages E² 50 are disposed in a circle around the fuel inlet, the air admitted through them and impinging against the under side of the valve head G serves to quickly dissipate the volatile oil and assist in vaporizing it as it 55 enters the chamber A. The valve head G is provided with an upwardly extending stem g' which serves as a guide and preferably extends through the top wall of the casing 1 where it co-operates with the mechanism em- 60 ployed for limiting its movement relatively to the opening of the auxiliary air passages.

The control of the air admitted to the carbureter to provide the explosive mixture of proper consistency for an engine working 65 under high duty presents a difficult problem

because of the different requirements of an engine under various working conditions, especially by reason of the frequent changes that occur in the temperature and humidity of the atmosphere and the differences in 70 the degree of gravity of the hydrocarbon fuels used at different times. In order to contend with these factors and to enable the carbureter to supply a carbureted mixture to the engine according to its needs and 75 which shall be automatic in its operation I have provided graduated air valve mechanism controlling the entrance of the auxiliary air admitted into the carbureter which is capable of being adjusted so that it will 80 come into action only when the speed of rotation, or work developed by the engine, has reached a given point. To this end I have arranged in the bottom of the chamber C an annular collar 2 having at its upper 85 edge a seat against which rests the valve head 3, provided with the depending side walls which guide the valve head on the collar, said walls being provided with a plurality of apertures 4 which are preferably 90 made V-shaped so as to form graduated openings increasing in area from the top of the wall downwardly. Extending upwardly from the valve head 3 is the tubular stem 5 guided in a central boss on the top plate 95 or cover 6 and surrounding the stem and resting on the valve head 3 is a weight 7 and a light coil spring 8, which parts co-operate to normally hold the valve head 3 in closed position until the resistance afforded by them is overcome by the partial 100 vacuum created in the carbureter casing.

The relative proportions of air and fuel admitted through the auxiliary inlets is controlled by means of a device which is operated by the opening movement of the air inlet valve 3, and arranged to act as a stop for limiting the opening movement of the fuel inlet valve G. The latter, it will be observed, is actuated similarly to the valve 110 3, by the inrushing currents of air, and the regulating or controlling mechanism which I employ for governing the movement of the auxiliary fuel valve G does not in any way tend to actuate it, but merely to control 115 its opening movement. This mechanism, in the present embodiment of my invention, comprises a pivoted member in the form of a bar 9 which extends over both valve heads, engaging the upper end of the valve stem g' 120 and projecting through a slot 10 in the valve stem 5. The desired position of the bar 9 in said slot is determined by the longitudinal adjustment of the screw threaded pin 11 in the stem 5 and the bearing member 12 125 yielding supported in the upper end of said stem and held in contact with the upper edge of the bar by means of the coil spring 13. The pivotal point 14 of the bar or member 9 is located adjacent the valve stem g', 130

and in order to permit the relative movements of the valve heads G and 3 to be varied slightly by the operator means is provided for shifting said pivotal point. 5 This is accomplished in the present instance by pivoting the bar 9 to a sliding rod 15, operated in one direction by a coil spring 16, movement of which in one direction is limited by a head 17 engaging a fixed 10 stop in the form of a boss 18. A lever 19, pivoted at 20, and having an end or extension 21, co-operates with the head 17 and serves to retract the rod 15 to increase 15 the distance between the fulcrum point 14 of the lever 9 relatively to the auxiliary air and fuel inlet valves.

In practice I have discovered that considerable latitude exists in the selection of the weight 7 and spring 8 and that these 20 need not be adjusted to such a degree of fineness that the auxiliary valves are permitted to open at the point where the maximum power is obtained from the carbureted mixture supplied through the main air and 25 fuel inlets F and D because, if means is provided for supplementing the air admitted through the channel F, a slight increase in power may be obtained over the maximum power which it is possible to produce by 30 means of the main inlets working alone. This is due to the fact that the suction produced at the nozzle D may become sufficient to draw in too great a volume of gasoline in proportion to the air admitted through the 35 channel F, thus producing too rich a mixture. Therefore, in order to utilize the full advantage of a maximum discharge of liquid fuel from the nozzle D, without the attending difficulties encountered in the enlarging 40 of the passage F, I provide a subsidiary air inlet passage which will supply to the carburetor the volume of air that is required to maintain a proper carburization during the interval between the time the main inlets 45 together have reached their maximum efficiency and the moment the auxiliary air and fuel valves 3 and G are allowed to come into action.

The subsidiary air inlets are, for convenience, formed by perforating the cover 6 of the chamber C, as indicated by 22, the area of the latter being adjustable by a similar perforated damper plate 23, which is held in place by means of the set screw 24. 55 The apertures 22 are normally closed by a disk 25 sliding on the stem 5 and normally held in its uppermost position against the under surface of the cap 6 by means of the spring 8, the tension of which may be increased or decreased by advancing or 60 retracting the collar 2 which is threaded into the bottom of the chamber C for this purpose, although it will be understood that other means may be employed for changing 65 the tension of the spring 8.

In order to describe succinctly the operation of a carburetor embodying my invention, it will be assumed that the device is used in connection with a motor employed for operating an automobile and the work 70 performed thereby will be indicated by the rate of travel of the vehicle. In the first instance the operator adjusts the needle valve d^2 of the discharge nozzle D to supply the requisite quantity of liquid fuel under ordinary operating conditions of speed varying from three to seventeen miles per hour, which adjustment remains constant for a fuel of specific gravity. The weight 7 used to restrain the action of the auxiliary air 75 valves 3 is proportioned so that the valve is retained closed until the work performed by the engine is sufficient to drive the vehicle at a rate of twenty-five miles per hour, or a lower speed slightly in excess of 80 the maximum speed obtainable from the combined action of the nozzle D and air inlet F. The maximum speed just referred to is the speed which is obtained just prior to the instant when the carbureted mixture 85 from the main inlets becomes too rich and supposing, for purposes of illustration, that this is a speed of seventeen miles per hour, the operator then adjusts the damper plate 90 23 and the tension of the spring 8 so that the subsidiary valve plate 25 will be opened to admit the supplementary supply of air sufficient to relieve the over richness of the carbureted mixture from said main air and 95 fuel inlets F and D and to provide the 100 volume of explosive mixture needed to carry on the engine operations until the speed attained is sufficient to produce a suction in the passage A which will open the auxiliary air and fuel supply inlets 3 and G. The 105 inward movement of the air valve 3 compresses the spring 8 and substantially closes the valve disk 25, whereupon the volume of air cut off by the latter finds ingress through the graduated apertures 4. The upward 110 movement of the valve 3 carries with it the bar or member 9, rocking the latter about its pivot 14 and moving it out of contact with the stem g' of the fuel inlet valve G. The latter being thus relieved is permitted 115 to open through the action of the inrushing air entering the ports or passages E^2 which, as before described, also assists in volatilizing the hydrocarbon fuel flowing from the passage e , which becomes very thoroughly 120 mixed with the greater volume of air entering beneath the valve head 3.

A carburetor constructed in accordance with my invention comprises a set of air and fuel inlets which, after being once adjusted are capable of furnishing a carbureted mixture of the proper proportions for all low speed operations and an additional set of air and fuel inlets co-operating with those first mentioned which will care for the 125 130

higher speed operations up to and including the maximum power which an engine is capable of developing, and by reason of the arrangement of the parts and the inclusion of the subsidiary air valve there is no point in the operation of an engine from its lowest to its highest speed where it receives a mixture of too great richness.

I claim as my invention:

10. 1. A carbureter comprising a chambered casing having direct and indirect air inlets and provided with an outlet for carbureted mixture, and liquid fuel inlets associated with said air inlets, of valves normally closing the indirect air inlet and its associated fuel inlet, said indirect air and fuel valves being each adapted to be operated independently by inrushing air and means for controlling the movement of the fuel valve relatively to that of the air valve.

20. 2. A carbureter comprising a chambered casing having two air inlets and provided with an outlet for carbureted mixture, and two liquid fuel inlets associated one with each air inlet, of two valves, one normally closing one air inlet and the other the corresponding fuel inlet, said valves being each arranged to be opened independently by the inrushing air.

30. 3. A carbureter comprising a chambered casing having a plurality of air and liquid fuel inlets arranged in pairs, and a valve normally closing one of the air inlets, and adapted to be opened by inrushing air, a second valve controlling the fuel inlet associated with the normally closed air inlet and also adapted to be opened independently by the inrushing air and means operated by the air valve for limiting the opening movement of the fuel valve.

40. 4. A carbureter comprising a chambered casing having separate air inlets for high and low speed engine operations, and liquid fuel inlets associated one with each air inlet, of graduated valves controlling the air and fuel inlets used for the high speed operations, a pivoted lever rocked by said air valve and coöperating with the fuel valve to limit its opening movement relatively to the opening movement of the air valve.

50. 5. A carbureter comprising a chambered casing having separate air inlets for high and low speed engine operations, and liquid fuel inlets associated one with each air inlet, of valves normally closing one set of air and fuel inlets each adapted to be opened independently of the other by inrushing air used for high speed operations, a lever rocked by the air inlet valve and arranged to govern the opening movement of the fluid inlet valve, and means for shifting the fulcrum point of the lever relatively to the last named valve.

60. 6. A carbureter comprising a chambered casing having separate air inlets for high

and low speed engine operations, and liquid fuel inlets associated one with each air inlet, of valves normally closing one set of air and fuel inlets, adapted to be opened by inrushing air, a lever pivoted in proximity to and coöperating with the fuel and air valves and means for adjusting the pivotal point of the lever in a direction toward and from the fuel valve.

70. 7. A carbureter comprising a chambered casing having separate air inlets for high and low speed engine operations, and liquid fuel inlets associated one with each air inlet, of valves normally closing one set of air and fuel inlets adapted to be opened by inrushing air, a lever extending over and coöperating with both of said valves and an adjustable pivoted support for one end of the lever.

8. The combination with a carbureter comprising a casing and means for forming a carbureted mixture therein, of auxiliary means for supplying a carbureted mixture comprising an air inlet in the casing and a liquid fuel inlet associated therewith, valves opening inwardly into the casing and normally closing said inlets, each adapted to be operated independently of the other by inrushing air, and a regulating member operated by the opening of the air valve and overlying the fuel inlet valve arranged to act as a limiting stop governing the opening movement of said fuel inlet valve.

9. The combination with a carbureter casing having an auxiliary air port, an auxiliary fuel inlet opening into the casing, a valve normally closing the air port and a separate valve normally closing the fuel inlet and arranged to be opened by inrushing air independently of said air valve, of means coöperating with both valves and governing their relative opening movements to proportion the supply of air and fuel admitted to the casing.

10. The combination with a carbureter casing having an auxiliary air port, an auxiliary fuel inlet opening into the casing a valve normally closing the air port and a separate valve normally closing the fuel inlet, of a pivoted lever coöperating with and governing the relative opening movement of both valves and means for shifting the pivotal point of the lever to vary the movement permitted the fuel inlet valve.

11. A carbureter comprising a casing having main air and fuel inlets and provided with auxiliary and subsidiary air inlet passages, and an auxiliary fuel inlet opening into the casing, of a valve normally closing the auxiliary air inlet, a second valve normally closing the auxiliary fuel inlet and a member controlled by the auxiliary air valve coöperating with the auxiliary fuel valve and forming a stop limiting its opening movement.

12. In a carbureter, the combination with a casing having an air inlet, a valve head normally closing it and a liquid fuel inlet opening into the casing, there being air inlet apertures surrounding said fuel inlet, of a valve head normally closing the fuel inlet and the apertures, a bar extending over said valve heads and movable with each about a pivot located in juxtaposition to the fuel inlet valve and limiting the opening movement of the latter relatively to the air valve.
13. In a carbureter, the combination with a casing having an air inlet, a valve head normally closing it and a liquid fuel inlet opening into the casing, there being air inlet apertures surrounding said fuel inlet, of a valve head normally closing the fuel inlet and the apertures, a bar extending across and coöperating with the two valve heads, a member on which it is pivoted adjustable relatively toward and from the fuel supply valve and varying the relative amplitude of movement of the air and fuel valve heads.
14. A carbureter comprising a casing having main and auxiliary air inlets and provided with a subsidiary air passage, of main and auxiliary fuel supply inlets associated with the main and auxiliary air inlets, means restraining the entrance of fuel and air in said auxiliary inlets, a valve controlling the subsidiary air passage and adjustable means for controlling said valve to permit it to open in advance of the opening of said auxiliary inlets.
15. A carbureter comprising a casing having a main set of air and fuel inlets, an auxiliary set of air and fuel inlets and valves normally closing the latter, of an air inlet supplementing the air supplied by the main air inlet, a valve normally closing said subsidiary air inlet and means controlling its operation and permitting said valve to open in advance of the opening of the auxiliary air valve and to be substantially closed upon the opening of said auxiliary air valve.
16. A carbureter comprising a casing having a primary set of normally open air and fuel inlets, a set of auxiliary air and fuel inlets and valves normally closing the latter and adapted to be automatically opened, of a subsidiary air inlet, a valve head coöperating therewith, means normally holding the valve head in closed position and permitting it to open in advance of the opening of the auxiliary air inlet, said means coöperating with the auxiliary air valve when opening to cause the subsidiary air valve to be substantially closed.
17. A carbureter comprising a casing having a primary set of normally open air and fuel inlets, a set of auxiliary air and fuel inlets and valves normally closing the latter and adapted to be automatically opened, of a subsidiary air inlet, a valve head coöperating therewith, a spring normally holding it in closed position and resting on the auxiliary air valve and adapted to be compressed upon movement of the latter, and means in addition to said spring for restraining the opening movement of said auxiliary air valve.
